(57) CLAIM

The ornamental design for a speaker pod, as shown and described.

DESCRIPTION

FIG. 1 is a top, front, right side perspective view of embodiment one, of a speaker pod, showing the new design; FIG. 2 is a front view of the speaker pod shown in FIG. 1; FIG. 3 is a rear view of the speaker pod shown in FIG. 1; FIG. 4 is a left-side view of the speaker pod shown in FIG. 1;

FIG. 5 is a right-side view of the speaker pod shown in FIG. 1;

FIG. 6 is a top view of the speaker pod shown in FIG. 1; FIG. 7 is a bottom view of the speaker pod shown in FIG. 1; and,

FIG. 8 is a top, front, right side perspective view of embodiment two, of a speaker pod, showing the new design, wherein the front, sides, top, and bottom views are mirror images of embodiment one.

The broken lines in the figures illustrate the portions of the speaker pod that form no part of the claimed design.
